Harry A. Searle,

by his attorney,

Charles R. Searle.

UNITED STATES PATENT OFFICE.

HARRY A. SEARLE, OF COUNCIL BLUFFS, IOWA.

GREASE-DRUM.

1,377,285.

Specification of Letters Patent. Patented May 10, 1921.

Application filed September 18, 1919. Serial No. 324,672.

To all whom it may concern:

Be it known that I, HARRY A. SEARLE, a citizen of the United States, residing at Council Bluffs, in the county of Pottawattamie and State of Iowa, have invented a certain new and useful Improvement in Grease-Drums, of which the following is a specification.

The invention relates to drums in which heavy oils or transmission greases are contained and transported, having an inclosed pump by which the contents may be delivered as required, and the object of the invention is to provide simple pump-operating mechanism which shall be economical in manufacture, easily installed, and positive and efficient in operation.

The invention consists in certain novel features and details of construction and arrangement by which the above and other objects are attained, to be hereinafter described and claimed.

The accompanying drawings form a part of this specification and show the invention as it has been carried out in practice.

Figure 1 is a front elevation of the improved drum with a portion broken away to show the contained pump and its operating means.

Fig. 2 is a vertical section taken on the line 2—2 in Fig. 1, and partly in elevation.

The remaining figures are on a larger scale and show details of the operating mechanism.

Fig. 3 is an elevation, partly in vertical section, showing the upper end of the vertical drive-shaft with its bearing and adjacent parts.

Fig. 4 is a vertical section showing the lower bearing for the drive-shaft and its connections to the pump-shaft, and is partly in elevation.

Similar letters of reference indicate the same parts in all the figures.

A is the cylindrical shell or body of the drum, of heavy sheet steel as usual, having a closed bottom A¹, and flanged top A² adapted to receive a close fitting cover A³ held in place by any suitable means, not shown.

B is a bar extending across the interior of the drum near the bottom A¹, serving to support a rotary pump C of any approved type secured thereon and having its suction orifice located as low as practicable so as to draw upon the contents near the bottom of

the drum and permit as nearly as possible the complete emptying of the drum.

The shaft C¹ of the pump extends through a sleeve D on a casting having a vertical tubular extension D¹ at a right angle thereto, and the shaft carries on its projecting end a large beveled gearwheel E. The upright extension D¹ is bored to receive the lower end of a vertical drive-shaft F and serves as a step for the latter supported by the pump-shaft C¹. On the drive-shaft F is a beveled pinion F¹ in mesh with the wheel E, see Fig. 4.

At its upper end the vertical drive-shaft F is inclosed by a depending tubular extension G¹ from an angular casting G having a horizontally disposed branch G² extending across the axial line of the extension G¹, as shown in Fig. 3. The branch G² has in its under face a recess g in axial alinement with the bore in the extension G¹ and receives the upper end of the drive-shaft F. A beveled pinion F² is secured on the upper end of the shaft F in the space between the extension G¹ and branch G².

H is the operating-shaft extending diametrically across the drum near the top, with its inner end supported in a boss or thimble A⁴ on the interior of the drum, and its outer squared end H¹ projecting into a socket A⁵ opening to the exterior of the drum and adapted to permit the application of a crank, not shown, to the squared end H¹, as will be understood.

The operating-shaft H passes through a stuffing-box J on the inner end of the socket A⁵, and through the horizontal branch G² of the casting G, and carries a beveled pinion H² in mesh with the pinion F² secured to the shaft F. Collars H³ H⁴ hold the shaft H against movement axially.

The delivery pipe C² of the pump extends vertically from the upper portion thereof and thence horizontally and radially to a boss K projecting into the interior of the drum, and having a screwthreaded orifice preferably of the same size and thread as the recess a in the boss A⁵, above described, so that interchangeable screwplugs, not shown, may be received to close these openings during transportation. The boss K is also adapted to receive the threaded coupling M¹ of a delivery hose M through which the grease or other lubricant is delivered from the pump.

In operating the pump the crank, not shown,

is applied on the squared end of the operating-shaft H and the latter turned, the motion being transferred through the beveled pinions F² H² to the drive-shaft F, and 5 through the beveled pinion F¹ and gear-wheel E to the pump-shaft C¹.

It will be noted that the castings D and G are supported solely by the shafts which they inclose. The long branch G² of the 10 casting G insures the latter against horizontal torsional movement, while the extension G¹ and recess g form a long bearing for the upper end of the drive-shaft F above and below the pinion F² and the said shaft F is held against vertical movement. At the 15 lower end the shaft F finds a long bearing and step in the extension D¹ of the casting or sleeve D which is mounted on the pump-shaft C¹ and confined thereon by the beveled 20 gearwheel E.

Thus arranged the shafts and gearing perform their functions efficiently and the expense of fixed bearings is avoided.

The pump is shown as supported on the 25 bar B extending on a chord across the drum, but it may be mounted on a base secured to the bottom A¹ or otherwise firmly held above such bottom.

I claim:

30. 1. The improved grease drum herein described, comprising a receptacle, a pump therein, a transverse pump supporting bar within said receptacle, the shaft of said pump being extended, a casting embodying 35 a sleeve receiving and supported by said shaft extension, said casting having an upright extension with a bore, a drive shaft stepped in said bore, intermeshing pinions on the drive shaft and pump shaft exten-

sion, an angular casting one member of 40 which is formed with a branch extended across and which receives the upper end of the drive shaft, an operating shaft transversely supported within the receptacle near its upper end and received in the other member of 45 said angular casting, and intermeshing pinions on the operating shaft and the upper end of the drive shaft.

2. In an apparatus of the character set forth, a drum, a pump therein having a 50 horizontally disposed pump-shaft, a sleeve loosely inclosing said pump-shaft and supported thereby, a vertical drive-shaft, an upwardly extended vertical extension on said sleeve serving as a step for said 55 drive-shaft and as a lower bearing therefor, a horizontally disposed operating-shaft and bearings therefor, a casting having a tubular branch inclosing said operating-shaft and supported loosely and 60 directly by the latter, a vertical depending tubular extension on said casting forming an upper bearing for said drive-shaft, and beveled gears between said operating-shaft and drive-shaft, and between said drive- 65 shaft and pump-shaft said branch having a depending portion with recess forming a bearing for the upper end of the drive-shaft above the bearing formed by said extension and above the upper gear wheel carried 70 by said drive-shaft.

In testimony that I claim the invention above set forth I affix my signature, in presence of two witnesses.

HARRY A. SEARLE.
